HARNESS OPERATING MECHANISM FOR LOOMS

William J. Oothout, Queens Village, N. Y.

Application June 27, 1936, Serial No. 87,699

3 Claims. (Cl. 139—55)

This invention relates to a novel and improved form of harness operating mechanism for looms, the novel features of which will be best understood from the following description and the annexed drawings, in which I have shown a selected embodiment of the invention and in which:

Fig. 1 is an elevation of the back of a loom frame having my invention applied thereto, only those parts of the loom which are necessary to an understanding of the invention being shown;

Fig. 2 is a view taken from the left of Fig. 1;

Fig. 3 is a fragmentary view on an enlarged scale taken on the same plane as Fig. 1, but showing the parts in different positions;

Fig. 4 is a view similar to Fig. 2 but with parts broken away and shown in section and showing various parts in different positions;

Fig. 5 is a view on an enlarged scale but on the same plane as Fig. 1 and showing certain elements in different positions;

Figs. 6 and 7 are diagrammatic views on the same plane as Fig. 5 and illustrating the operation of the invention;

Figs. 8, 9, 10, and 11 are diagrammatic views illustrating the operation of the invention;

Figs. 8A, 9A, 10A, and 11A are views corresponding, respectively, to Figs. 8, 9, 10, and 11 and showing the positions of the parts which operate the heddle frame.

The invention relates to a mechanism for operating a harness on a loom, which harness is designed to form the shed in the warp. Devices have been used for operating the harness, but my invention is designed to provide certain improvements in the prior art mechanisms, which improvements will become evident or will be pointed out as the description progresses.

The frame of the loom may take any suitable form and is indicated generally by the numeral 1. Mounted on that frame is a lay sword 2, on the upper end of which is a lay 3 including a reed 4. The other details of the lay and of the loom have been omitted, as they may vary widely without affecting the invention.

The warp 5 is wound upon a beam 6, and at the lay it should have its threads separated into a shed, such as indicated at 7, this formation of the shed taking place repeatedly and at closely timed intervals during the operation of the loom, as understood by those skilled in the art.

In order to form the shed, I employ a harness comprising a plurality of frames 8, each of which has a plurality of heddles 9 carried thereby, each heddle having an opening therein through which one or more threads of the warp pass. The details of the heddles and frames likewise may vary widely without affecting the invention, and so they will not be described further. The shed is

formed by raising certain threads of the warp and by depressing other threads, both the raising and depressing being from the normal plane occupied by the warp. It is to the means for operating the raising and lowering of the frames that my invention relates.

Each frame 8 is shown as being supported by a plurality of spaced cables 10 and 11 shown as connected together at 12 to a third cable 13 which engages in a groove on a cone-shaped pulley 14. I provide two such pulleys, shown as one above the other, and in the illustrated embodiment alternate frames are operated by cables 13 connected to the lower pulley 14 and the intermediate frames are operated by cables 15 connected to the upper pulley 16.

Each pulley is preferably of the construction indicated in Fig. 4, for example, where it is seen that the pulley is generally conical in shape, being provided with a plurality of parallel circumferential grooves, in each of which is a suitable hook 17 to engage a loop on the end of a cable. The lower cone is mounted on a shaft 18 and the upper on a shaft 19 which have secured thereon gears 20 and 21, respectively, which mesh with an idle pinion 22 so that the two gears rotate simultaneously in the same direction. Rotatably mounted on the shafts 18 and 19 are sleeves or hollow shafts 23 and 24, respectively, to which are secured gears 25 and 26 meshing with an intermediate pinion 27.

Each cone is preferably a double or duplex cone having a front half 28—28' nearest the front of the loom, and a rear part 29—29'. The parts 28 and 28' are secured, respectively, to the shafts 18 and 19 to rock therewith, whereas the parts 29 and 29' are secured to the sleeves 23 and 24, respectively.

Since the cables 13 are wound in a counter-clockwise direction around the pulley 14, and the cables 15 are wound in a clockwise direction around the pulley 16, and since these pulleys rotate simultaneously in the same direction, it will be seen that such rotation will cause opposite movements of the frames to which the respective cables are connected. For example, if the frames operated by the cables 13 are raised, then the frames connected to the cables 15 will be released so that they may drop, and a positive depressing of these frames connected to the cable 15 is insured by connecting alternate frames to cables 30 which have their opposite ends connected to adjacent frames and extending around conically shaped pulleys 31. These pulleys 31 are duplex, the same as the pulleys 14 and 16, but are idle, thereby insuring that the upward movement of one frame will be accompanied by an equal and simultaneous downward movement of the next adjacent frame.

I have shown the heddle frames as being operated from the shaft 32 upon which is mounted a bevel gear 33 meshing with a similar gear 34 on the crank shaft 35 which operates the lay 5 through links 36, all as known in the art.

Mounted on the shaft 32 are two eccentric gears 37 and 38 meshing, respectively, with elliptic gears 39 and 40 mounted on stub shafts on the frame of the shaft so that they may operate independently of each other.

The gears 39 and 40 have crank pins 41 and 42 thereon connected to links 43 and 44 and these links at their opposite ends are pivoted to rock arms 45 and 46. Each of these arms has on its 15 upper end gear segments 47 and 48, respectively, which mesh with the gears 20 and 25.

In operation, the shaft 35 is rotated by any suitable driving mechanism from any suitable source of power, both of which have been omitted 20 as not necessary to an understanding of the invention. The warp is pulled from the beam 6, likewise by any suitable mechanism which has been omitted, and the lay, shuttle, and other parts of the loom operate in the usual manner.

Assume first that the parts are in the position indicated in Fig. 8, where the threads of the warp are all in a single horizontal plane and the heddle frames are in what may be considered their normal position. Assume also that the frame designated 8-1 is operated by the rear half 29 of the lower pulley 14, while the frame designated 8-2 is operated or controlled by the rear half 29' of the upper pulley 16. Similarly, assume that the frame designated 8-3 is controlled by the front half 28 of the lower pulley 14, whereas the frame 8-4 is controlled by the front half 28' of the upper pulley 16. For the sake of simplicity, I have shown only one frame controlled by each part of a duplex pulley, although it will be understood that the number of frames controlled by each part may vary as desired, depending upon the size of the pulley, which in turn will depend upon the particular job involved.

With the frame and the warp in the position shown in Fig. 8, the gears 37, 38, 39, and 40 will be in approximately the position shown in Fig. 8A. It will be seen that the gears 37 and 39 are of slightly different form than the gears 38 and 40, the forms being designed to cause the operation 50 which will now be more fully described. As the operation progresses, the gears will reach some such position as shown in Fig. 9A, which will cause the frames to take the positions indicated in Fig. 9. It will be seen that the frames 8-1 and 8-2 have been moved to a greater extent than the frames 8-3 and 8-4, this being the result of the difference in the gears just mentioned above. In turn, the result of this difference in motion of the frames is to cause a separation of 55 the threads in the shed which is being formed, thus facilitating the formation of a clear shed.

As the operation continues, the parts reach some such position as shown in Figs. 10 and 10A, where it will be seen that the shed is uniform, all 60 of the threads which have been raised being raised in equal amount, and those which have been depressed being depressed in equal amount. Then, as the operation continues, the frames which have been raised will now become lowered, 65 and those which have been lowered will be raised, as indicated in Figs. 11 and 11A, showing the cor-

responding positions of the parts 39 and 40. The positions indicated in Figs. 8 and 10 are positions which may be termed neutral, since there is no separation between threads in the shed except the major separation between those which are raised and those which are lowered.

From the above it will be seen that I have provided a novel and improved means for forming a shed and for facilitating the formation of a shed which will be clear. This is of particular 10 importance where the warp is a dense one made up of many fine threads or very fibrous threads which are apt to stick together. By introducing the lag between the threads which are to be raised so that some are raised in advance of the others, it is possible to separate those threads and overcome their tendency to stick together, and, of course, the same is true of those threads which are depressed.

It will be noted that the cone shape of the pulleys will cause a raising of some frames more than others, the amount of raising corresponding generally to the angle of the threads in the two parts, upper and lower, of the shed. That is to say, each part of the shed is formed of threads disposed in an inclined plane, and the inclination of that plane is approximately the same as the inclination of the cones. Since the various cables are connected to the pulleys by means of hooks engaging loops on the cables, the cables 30 may be changed from an upper to a lower pulley or vice versa, and thus the operation of the frames by the pulleys may be varied.

I claim:

1. In a loom, a harness comprising a plurality of frames each having means engaging certain threads of a warp, a pair of spaced pulleys one connected by cables to alternate frames and the other to the intermediate frames, means to rotate said pulleys in unison and in such directions 35 that the alternate and intermediate frames will move in opposite vertical directions to separate the threads of the warp into the two parts of a shed, each of said pulleys having two parts, and means for actuating one part with a different motion than the other.

2. In a loom, a harness comprising a plurality of frames each having means engaging certain threads of a warp, a pair of spaced pulleys extending lengthwise of said warp, one of said 50 pulleys being connected by cables to alternate frames and the other to the intermediate frames, means to rotate said pulleys in unison and in such directions that the alternate and intermediate frames will move in opposite vertical directions to separate the threads of the warp into the two parts of a shed, each of said pulleys having two parts, and means for actuating one part with a different motion than the other.

3. In a loom, a harness comprising a plurality of frames each having means engaging certain threads of a warp, means to operate said frames to form a shed, said means comprising a pulley connected by cables to those frames engaging the threads in one half of the shed, said pulley being formed in two parts spaced center to center lengthwise of the longitudinal axis of the pulley, and means for positively rotating said parts simultaneously but independently of each other and with different motions.

WILLIAM J. OOTHOUT.
